1

This invention relates to improvements in phase-shifting devices and in particular to such devices as are operative to produce substantially constant voltage output.

It is a prime objective of the invention to provide improved means for producing from a substantially constant voltage an adjustably variable phase shift at a second substantially constant voltage.

Other objects and various further features of novelty and invention will hereinafter be pointed out or will become apparent to those skilled in the art from a reading of the following specification in connection with the drawing included herewith. In said drawing—

Fig. 1 is a schematic diagram of a basic phase-shifting circuit;

Fig. 2 is a vector representation of voltages appearing in the circuit of Fig. 1; and

Fig. 3 represents an improved circuit illustrating a method of effecting a phase shift electronically in accordance with the invention.

Phase shifting devices have been suggested wherein manual operation of certain circuit elements is required to effect the desired phase shift. Some of these devices have been of the nature shown in Fig. 1 wherein input voltage is applied across a voltage-dividing device having a center-tap. In the form shown, this divider is a resistive potentiometer and comprises two equal impedances R_1 and R_2 . Across the potentiometer are connected two further impedances, one of which has a characteristic in phase quadrature with that of the other. In the form shown, one of these further impedances R_3 is resistive and the other C_1 is capacitatively reactive. If the applied voltage at the input is substantially constant, a substantially constant voltage may be taken from between the center-tap of the potentiometer and a point between impedances R_3 and C_1 . By adjusting the relative magnitudes of R_3 and C_1 , the phase but not the voltage magnitude of the output may be correspondingly adjusted.

This effect may be more clearly illustrated by the vector diagram of Fig. 2 wherein it will be seen that input voltage is uniformly divided between impedances R_1 and R_2 , as illustrated by the equal vectors V_{R_1} and V_{R_2} . Since output is taken from the center-tap of the potentiometer, the juncture of vectors V_{R_1} and V_{R_2} defines one end of the output voltage vector V output. Since the characteristics of impedances R_3 and C_1 are always in quadrature with respect to each other and further since the voltage across them always equals the sum of V_{R_1} and V_{R_2} , the vector locus

of the voltage at a point between them lies on a semi-circle having a radius equal to V_{R_1} or V_{R_2} . Since the output is taken from between the center-tap and a point between impedances R_3 and C_1 , the vector representing this voltage will always be equal to the radius of the semi-circle and hence constant.

In accordance with the invention, the relative magnitudes of the quadrature impedances may be electronically controlled by the use of a vacuum tube having a resistive impedance characteristic which may be varied by varying the grid bias. Such a circuit is shown in Fig. 3 wherein the potentiometer comprising impedances R_1 and R_2 will be recognized. For the sake of simplicity, the circuit of Fig. 3 has been shown to include means for varying only one of the quadrature impedances, namely, the resistive one. In the form shown, this means comprises a variable μ triode T having a variable resistance R_4 in its grid circuit. A large blocking condenser C_2 connects one end of resistor R_4 to the input side of impedance R_1 and to the anode circuit of tube T . Another blocking condenser C_3 connects the other side of resistor R_4 to the cathode circuit of tube T . Condenser C_1 representing the reactive portion of the impedances across the potentiometer is connected to the cathode circuit of tube T .

Considering the input of the circuit of tube T as between anode and cathode, the resistance Z_R of this tube will appear as

$$Z_R = \frac{R_p}{\frac{\mu e_s + E_p}{E_p}} = \frac{R_p}{\frac{\mu e_s}{E_p} + 1}$$

where E_p is the signal voltage applied to the anode of tube T from input I , R_p is the plate resistance of tube T , and e_s is the magnitude of signal voltage from input I which is applied to the grid as controlled by the setting of potentiometer R_4 .

With the circuit thus described, it will be clear that the resistive impedance branch represented by tube T may be adjustably controlled by hand in accordance with the setting of potentiometer R_4 . To get an idea of the magnitude of phase control obtainable in this manner, it is convenient to consider the condition when e_s is made equal to E_p , at which time Z_R becomes equal to

$$\frac{R_p}{1 + \mu}$$

On the other hand, further variation in the effective resistance offered by tube T may be seen as limited by e_s being so small that Z_R becomes equal

substantially only to R_p . It is thus clear that a relatively wide range of manually controlled phase shifts may be obtained with the circuit of Fig. 3.

For any particular manual setting of effective resistance offered by the circuit of tube T, as made in the above manner, electric control thereof may be effected by application of a desired control-signal pattern at point P. In this manner grid bias is varied in accordance with the control signal and, in the assumed case of a variable μ tube, so is the μ of tube T. It is thus clear that a relatively wide range of electronic control of phase shifts is possible for any particular manual setting of potentiometer R_4 , as above explained.

Although I have described my invention in detail in particular connection with the preferred form illustrated, it is to be understood that many modifications, additions, and omissions may be made fully within its scope, as defined by the appended claims.

What is claimed is:

1. Means for offering an apparent variable resistance varying in accordance with a control signal comprising a discharge device including an electron-emissive electrode, a control electrode, and an electron-collecting electrode, adjustable voltage-dividing means, condenser means coupling one end of said adjustable voltage-dividing means to said electron-collecting electrode to form one terminal of said apparent variable resistance, condenser means coupling the other end of said adjustable voltage-dividing means to said electron-emissive electrode to form the other terminal of said apparent variable resistance, means for applying said control signal across said adjustable voltage-dividing means, and means for applying a biasing potential through said voltage-dividing means to said control electrode independently of said control signal.

2. Apparatus according to claim 1, wherein said means for applying a biasing potential is connected to apply said biasing potential to one end of said voltage dividing means.

3. In a phase shifting circuit having a voltage dividing means across which input energy is applied, a vacuum tube having plate, cathode and grid electrodes, and a condenser connected between one end of said voltage divider and said cathode electrode, the plate electrode being connected to the other end of said voltage dividing means; means for controlling the impedance of said tube comprising a second condenser connected to said plate electrode, a bias voltage source for said grid electrode, a potentiometer therefor with connections therefrom to said second condenser, to said voltage bias source and to said grid, whereby adjustment of said potentiometer controls the impedance of said tube.

4. In a phase shifting circuit according to claim 3 wherein said potentiometer includes a resistance and an adjustable contact, said resistance being connected between said second condenser and said voltage bias source and said adjustable contact being connected to said grid electrode.

5. A translating system comprising a voltage dividing means having center tap and outer terminals for application of an input voltage thereto, a series connection of component impedances between said terminals and with its components connected together at an intermediate point, one impedance component comprising a potentiometer resistance and an electron discharge device having a control electrode, a biasing means therefor, and a plate-cathode circuit in shunt with said potentiometer resistance, connections between the adjustable element of the potentiometer and said control electrode, the component including the discharge device having an impedance characteristic substantially in quadrature with that of the other component, whereby a relatively large proportional change between said impedance components is producible in the voltage across said center tap and said intermediate point.
